UNITED STATES PATENT OFFICE.

FREDERICK SIEMENS, OF DRESDEN, GERMANY.

REGENERATIVE GAS REHEATING-FURNACE.

SPECIFICATION forming part of Letters Patent No. 767,840, dated August 16, 1904.

Application filed June 15, 1903. Serial No. 161,572. (No model.)

To all whom it may concern:

Be it known that I, FREDERICK SIEMENS, engineer, a subject of the King of Saxony, residing at 4 Liebigstrasse, Dresden, in the Empire of Germany, have invented certain new and useful Improvements in Regenerative Gas Reheating-Furnaces, of which the following is a specification, for which I have applied for a patent in Great Britain, dated November 14, 1902, No. 25,057.

For the purpose of reheating ingots, blooms, billets, and the like for rolling and hammering it has been proposed to employ regenerative gas-furnaces having one end of the hearth 15 cold or comparatively cool and the other end hot or at the desired finishing heat. In such furnaces as at present constructed, however, it is found that if one end of the bed is cold or comparatively cool the regenerators are not 20 heated regularly or sufficiently, with the result that the required temperature is not maintained at the finishing end of the furnace-bed.

The present invention consists in improvements in the construction of regenerative gas reheating-furnaces by which in such furnaces the regenerators are heated regularly and sufficiently to maintain the required temperature at the finishing end, while the other end may 25 always be comparatively cool or even cold, so that ingots, blooms, billets, and the like can be continuously charged at the cold end and worked along gradually to the hot end, becoming heated on the way, until at the extreme hot end they are drawn or pushed out 30 at the desired heat for rolling or hammering.

In the accompanying drawings, Figures 1 and 2 are respectively a vertical longitudinal section and a sectional plan showing the arrangement of the hot-end part of the furnace and the means for heating it consisting of an independent complete regenerative gas-furnace. Fig. 3 is a sectional plan showing the similar heating arrangements for the cooler part of 45 the furnace-bed in front of the partition-wall. Fig. 4 is a diagrammatic sectional plan showing the general arrangement of a complete furnace-bed constructed according to this invention, and Fig. 5 is a section on line 5 of 50 Fig. 4. Figs. 6 and 7 are views similar to

Figs. 4 and 5 of a modified construction of furnace to suit two rows of ingots. Fig. 8 shows a modified construction of the screen-wall. Fig. 9 is a part plan of a modified construction of the end furnace. Fig. 10 is a 55 vertical longitudinal section of a furnace similar to Fig. 4. Figs. 11 and 12 are cross-sections on lines 11 11 and 12 12 of Fig. 10, and Figs. 13 and 14 are diagrammatic sectional views of a further modification.

Referring to Figs. 1 and 2, A is the part of the furnace in rear of the partition-wall *e* in which the ingots or billets are brought to their finishing heat and is in communication with the gas-producers B B' through the flues C C' 60 and with the regenerators D D' through the flues E E'. Valves are provided for the control of the air and gas admitted and of the waste gases leaving the furnace according to well-known practice. The result obtained is 65 a **U** or horseshoe flame across the end of the heating-furnace reversible in direction, as represented by the arrow.

In Fig. 3 a complete independent regenerative gas-furnace is shown by which is obtained a similar **U** flame in the part F of the heating-furnace in front of the partition-wall, but directed lengthwise of the furnace.

Although, as shown in Figs. 1 to 3, provision is made for heating the regenerators 80 alternately and reversing the direction of the flame, it is to be understood that sometimes when a lower finishing heat is sufficient the direction of each flame may be continuous, the regenerators then being heated, as usual, 85 in a continuous manner.

According to the construction of furnace shown in Figs. 4, 5, 10, 11, and 12 the transverse partition-wall *e* has an opening on the level of the furnace-bed just sufficiently large 90 to allow the passage of a single ingot. The cold ingots are entered at the mouth *b* of the forward part of the heating-furnace and are gradually advanced, for example, by some mechanical device, such as *a*, into and through 95 the horseshoe flame *p*, extending between the flues from *d* to *c*, being thereby gradually heated, thence through the passage in the wall *e* into the region of the flame *f*, where it is brought to a finishing heat and from 100

which it is ejected through the opening *g* by any suitable means.

Figs. 6 and 7 show a double furnace of similar construction. In this case the partition-
5 wall may alternatively be built as shown in transverse section, Fig. 8. In each of these cases also the hot part of the furnace may be heated by a double continuous flame, as shown in the part-sectional plan, Fig. 9.

10 As shown in Figs. 10, 11, and 12, the ingots preferably travel on water-cooled tubes *k* on the bed of the cooler part of the furnace, which is also sloped to facilitate the transfer-
15 ence of the ingots. It is to be understood that the bed of the furnace shown in Figs. 6, 7, and 8 may also be provided with tubes and sloped.

Figs. 13 and 14 are respectively horizontal and vertical longitudinal sections of a furnace 20 arranged for the heating-flames in the cooler part of the furnace to pass alternately from side *h* to side *i* and from side *i* to side *h* of the furnace.

Having thus described the nature of this in-
25 vention and the best means I know of carrying the same into practical effect, I claim—

1. A regenerative gas reheating-furnace having primary and secondary chambers in communication with each other for the pas-
30 sage of billets, blooms or the like from the primary to the secondary chamber, means

whereby a gas-flame is directed across one of said chambers above the bed thereof and between the ends of said bed, said flame being of a gradually-increasing temperature from 35 one end of said bed to the other, and means for heating the other furnace-chamber.

2. A furnace having primary and secondary chambers in communication with each other for the passage of billets, blooms or the like 40 from one to the other, means whereby a substantially U-shaped gas-flame is directed across one of the chambers above and between the ends of the bed thereof, said flame being of gradually-increasing temperature from one 45 end of the bed to the other end, and means for heating the other furnace-chamber.

3. A furnace having a heating-chamber, and means whereby a substantially U-shaped gas-flame is directed across said chamber above 50 its bed and between the ends of the latter, said flame being of gradually-increasing temperature from the charging end to the finishing end of said chamber.

In witness whereof I have hereunto set my 55 hand in presence of two subscribing wit-
nesses.

FREDERICK SIEMENS.
